UNITED STATES PATENT OFFICE

2,569,419

SELF-ALIGNING CARRIER FOR BELT CONVEYERS

Myron A. Kendall, Aurora, Ill., assignor to
Stephens-Adamson Mfg. Co., a corporation of
Illinois

Application October 4, 1947, Serial No. 777,911

4 Claims. (Cl. 198—202)

1

This invention relates to belt conveyors with particular reference to "self-aligning" carriers for automatically returning the conveyor belt to "center" when for any reason it creeps to one side. As heretofore made, such carriers have consisted of ordinary carriers pivoted at the center to swing about a vertical axis when the belt creeps to one side and thus steer it back to center. Many such carriers have been equipped with guide rollers at each side at right angles to the edges of the belt to positively limit sidewise travel of the belt and to swing the carriers. But such guide rollers are hard on the edges of the belt and they are exposed to damage by large rocks or the like carried by the belt.

The principal object of this invention is to provide means that will be acted upon by the under surface of the creeping belt to positionally swing the carrier. Generally speaking, this is accomplished by mounting an auxiliary pulley or idler at each side of the carrier and positioned to be moved by the bottom of the belt when it creeps, and means operated by the pulley to swing the carrier to steer the belt back into line.

The preferred embodiment of the invention is illustrated in the accompanying drawings in which

Fig. 1 is a vertical cross-section through a conveyor;

Fig. 2 is a vertical longitudinal section on the line 2—2 of Fig. 1;

Fig. 3 is a diagram illustrating the operation of the self-aligning carrier;

Fig. 4 is a perspective view of a fulcrum bracket for mounting the auxiliary pulley; and

Fig. 5 is a plan view with the intermediate portions of the idlers broken away to show other parts of the device.

In the drawings, 10 indicates the side beams of a supporting structure spanned by a special underslung cross bar 11 in the middle of which there is a pivotal mounting 12 for a carrier composed of a base angle 13 and central and troughing pulleys or idlers 14 and 15 journaled on the shafts 16 and 17 and supported by brackets 18 and 19 fixed to the angle 13. Such carriers may be assumed to be old, are of the type furnished by Stephens-Adamson Manufacturing Co. of Aurora, Illinois, in connection with belt conveyors. In practice, one of the pivoted or swinging carriers is used for about each fifty feet of belt conveyor.

According to this invention, there are auxiliary idlers or pulleys 20, one at each side of the carrier, journaled on a shaft 21, adjustably mount-

2

ed in the upper arm 22 of a two-arm bracket fulcrumed on a shaft 23, carried by a fulcrum bracket 24, adjustably mounted on the upturned end 25 of the angle 13, and having a lower arm 26 connected by a thrust link 27 with the depressed cross bar 11.

Preferably the auxiliary pulleys 20 are so adjusted as to have slight contact with the edged portions of the conveyor belt 29 as indicated by the arrows 30, so as to be immediately brought into action when the belt creeps to one side. In fact, they are always in action, but their actions being equal, there is no effect on the pivoted carriers. But as soon as the belt creeps to one side, the pressure of the under surface of the belt on the auxiliary pulley 20 will act upon the shaft 21 and the arm 22 to swing the two-arm lever about the fulcrum 23 and push the thrust arm 27 against the cross bar 11, thereby swinging the carrier about the pivot 12 in a direction to steer the belt back to center.

The action is illustrated in the diagram in Fig. 3, where the pressure of the belt is indicated by the arrow 31, and acting upon the pulley 20 rotates the crank 35 as indicated by the arrows 36 and 37, and pushing against the thrust link as indicated by the arrow 38 which will swing the carrier in the direction indicated by the arrow 39 and steer the belt back to center.

The shafts 21 are made adjustable in the upper arms 22 of the brackets by passing them through cylindrical portions 41 and making them fast by set screws 42. The fulcrum brackets 24 have flat pieces 43 with elongated slots 44 to receive bolts 45 by which they may be adjusted lengthwise to the upturned end portions 25 of the angle 13. By means of these adjustments, the idlers 20 may be adjusted to suit the conditions and put them in position to immediately react through the means described to swing the carrier and steer the belt back to center.

As here shown, the links 27 have their outer ends bent at right angles and inserted through openings in the arms 26 where they are made fast by keys 46, and the inner ends are similarly turned at an angle to be inserted through the cross bar 11 and made fast by other keys 47.

These thrust rods are the only parts that need be changed to make the apparatus fit various widths of carriers.

The invention may be applied to a variety of troughing carriers regardless of the angle of the outer troughing rollers and the angle of the auxiliary pulleys will be varied to suit those con-

ditions. The angles shown in Fig. 1 have been found satisfactory in practice.

I claim:

1. In a device of the character described, a support, a troughing carrier including troughing pulleys mounted on a carrier cross member pivoted to the support to swing about an axis substantially at right angles to the cross member, an auxiliary pulley alongside each outer pulley of the carrier at a greater angle of inclination with a portion projecting above the respective outer pulley, a lever fulcrumed on the cross member and supporting each auxiliary pulley, and means for connecting the lever and the support.

2. In a device of the character described, a support, a troughing carrier including troughing pulleys mounted on a carrier cross member pivoted to the support to swing about an axis substantially at right angles to the cross member, an auxiliary pulley alongside each outer pulley of the carrier at a greater angle of inclination with a portion projecting above the respective outer pulley, a two-armed lever fulcrumed on the cross member with one arm bearing the auxiliary pulley, and means connecting the other arm with the support.

3. In a device of the character described, a support, a troughing carrier including troughing pulleys mounted on a carrier cross member pivoted to the support to swing about an axis substantially at right angles to the cross member, an auxiliary pulley alongside each outer pulley and adjacent the side of the carrier at a greater angle of inclination than the angle of inclination of said outer pulley with a portion projecting above the respective outer pulley, and means car-

rying said auxiliary pulley mounted on said carrier and attached to said support, whereby pressure upon each auxiliary pulley operates through said means to swing said carrier about said axis and thereby to guide a conveyor belt to center.

4. In a device of the character described, a support, a troughing carrier including troughing pulleys mounted on a carrier cross member pivoted to the support to swing about an axis substantially at right angles to the cross member, a lever fulcrumed on said troughing carrier adjacent each outer pulley, an auxiliary pulley mounted on each lever alongside the corresponding outer pulley at a greater angle of inclination than the angle of inclination of said outer pulley with a portion of said auxiliary pulley projecting above the respective outer pulley, and means connecting each lever and said support whereby pressure upon each auxiliary pulley operates through the associated lever to swing said carrier about said axis and thereby to guide a conveyor belt to center.
